UNITED STATES PATENT OFFICE.

HENRY H. VAUGHAN AND CHARLES HARRIS JOHNSON, OF CHICAGO,
ILLINOIS.

FLUID-PRESSURE-OPERATED TOOL.

SPECIFICATION forming part of Letters Patent No. 742,934, dated November 3, 1903.

Application filed January 14, 1902. Serial No. 89,751. (No model.)

To all whom it may concern:

Be it known that we, HENRY H. VAUGHAN and CHARLES HARRIS JOHNSON, citizens of the United States, residing at Chicago, county 5 of Cook, State of Illinois, have invented a certain new and useful Improvement in Fluid-Pressure-Operated Tools; and we declare the following to be a full, clear, and exact description of the invention, such as will enable others skilled in the art to which it pertains to make and use the same, reference being had to the accompanying drawings, which form a part of this specification.

Our invention relates in general to fluid-pressure-operated tools, and more particularly to pneumatic hammers of the valveless type.

In fluid-pressure-operated tools as ordinarily constructed the piston delivers a blow upon a snap or shank of the tool immediately before reaching one end of its stroke, the initial propulsion of the piston toward the tool being due to the flow of fluid-pressure from the source of motive-fluid supply, while the final portion of the stroke is due to the expansion of the fluid within the cylinder after the source of supply has been cut off. Fluid-pressure-operated tools have also been constructed heretofore in which impetus is given to the stroke of the piston by placing in communication with the cylinder a reservoir which has been charged with pressure coincidently with the admission of pressure to the working end of the cylinder from the motive-fluid supply; but it is obvious that in a tool so constructed the time available for charging the reservoir is limited to the time the induction-port remains open to the working end of the cylinder, and it is also obvious that the induction-port must remain open sufficiently long to charge the reservoir, as well as the working end of the cylinder, in order to avoid the reduction of the pressure in the working end of the cylinder at the beginning of the piston-stroke.

The primary object of our invention is to provide a fluid-pressure-operated tool in which the beginning of the stroke of the piston toward the tool is effected by the admission of pressure from the source of motive

fluid, while the continuation of the piston-stroke is effected by connecting the working end of the cylinder with a reservoir which has been charged with pressure from the motive-fluid supply prior to the admission of pressure to the working end of the cylinder. 55

A further object of our invention is to provide a tool of the class described which will be simple in construction and efficient in operation. 60

Our invention, generally stated, consists in a cylinder in which a piston reciprocates and a reservoir which is charged with pressure from the motive-fluid source during the throw of the piston away from the tool before the admission of pressure to the working end of the cylinder and which discharges into the cylinder after the piston has commenced its stroke toward the tool. 65

Our invention will be more fully described 70 hereinafter with reference to the accompanying drawings, and in which the same is illustrated as embodied in a convenient and practical form, and in which—

Figure 1 is a longitudinal section through 75 a tool embodying our invention, showing the piston delivering a blow upon the tool; and Fig. 2 is a similar view showing the piston at the beginning of its stroke toward the tool.

The same reference characters are used in 80 the two figures of the drawings to indicate the same parts.

Reference-letter A indicates a cylinder within which the piston D reciprocates. A handle B is secured to one end of the cylinder in any suitable manner. In the present instance a flange B' overlaps the end of the cylinder and is held in such position by a cap A', which is provided with a screw-threaded tubular portion a' in engagement 85 with the interior surface of the end of the cylinder. A flange b', formed on the handle B, is interposed between the head of the cap A' and the end of the cylinder A. Any suitable means may be provided for retaining 90 the cap A' from rotation with respect to the handle, such means being shown as consisting in a spring-actuated bolt b', engaging with ratchet-teeth on the rim of the cap A'. 95

A throttle-valve B⁵ is located within a 100

valve-seat B^6 , which is screwed into a tubular extension on the handle B , such valve controlling ports b^5 through the valve-seat.

B^4 indicates a coupling to which a pipe 5 leading from the motive-fluid supply is secured.

B^3 indicates a reciprocating spindle which at one end engages the throttle-valve B^5 and at its other end is engaged by a hand-operated lever B^2 , pivotally mounted in the handle B .

b indicates a passage in the handle B , communicating at one end with a passage controlled by the throttle-valve and its other end 15 in register with a passage a in the cylinder A . An annular chamber A^3 , formed in the cylinder, communicates with the other end of the passage a . A chamber A^5 is provided in the end of the cylinder opposite to the 20 handle B , such chamber communicating with the atmosphere through exhaust-ports a^5 . A ferrule E is fitted within the end of the cylinder adjacent to the chamber A^5 , in which a die or snap or the shank of a tool F is located. A bushing C is preferably located 25 within the cylinder A between the cap A' and the annular chamber A^3 . Series of ports c' c^2 c^3 are formed through the bushing C and communicate with a chamber A^2 , formed 30 in the cylinder A around the bushing. The series of ports c^3 are formed through the bushing between its closed end and the cylinder-cap A' .

The piston D is of a differential type and 35 is provided with a shoulder d' , formed between the main portion of the piston and the enlarged end thereof, D' . The piston is preferably hollow and provided with ports d , extending from the interior thereof to the 40 outer surface and located adjacent to the end of the piston opposite to the enlarged portion D' . The reduced portion of the piston D is of such a diameter as to closely fit the inner surface of the portion A^4 which 45 extends between the annular chamber A^3 and exhaust-chamber A^5 . The surface of the enlarged portion D' closely fits within the interior of the bushing C and is sufficient to simultaneously close both of the series of ports 50 c' and c^2 through the bushing C .

It will be obvious from the drawings that the various parts of the tool may be assembled by introducing the bushing C prior to inserting the cap A , so that an annular shoulder c^4 on the exterior of the bushing will engage the wall at the end of the chamber A^2 , while the opposite end of the bushing will be engaged by the end of the screw-threaded collar a' of the cap A' . The cap A' is inserted 55 in the proper position with respect to the handle B prior to screwing into the end of the cylinder A .

The operation of our improved fluid-pressure-operated tool is as follows: The handle-lever B^2 is depressed, as indicated in Fig. 2, 60 which through the interposed spindle B^3 depresses the throttle-valve B^5 , so that the lat-

ter uncovers the ports b^5 . Motive fluid consequently flows from the source thereof through the coupling B^4 , thence through the ports b^5 70 to the passage b , which registers with the passage a , which in turn communicates with the annular chamber A^3 .

The piston D being in the position indicated in Fig. 1, the motive fluid is exerted upon the shoulder d' and 75 causes the piston to move toward the handle, inasmuch as the larger end of the piston and also the cylinder and chamber A^2 therein are in communication with the atmosphere through the exhaust-ports d , the chamber A^5 , and the 80 ports a^5 .

When in the movement of the piston toward the handle the enlarged portion D' uncovers the ports c' , motive fluid is admitted through such ports to the chamber A^2 85 and also through the series of ports c^3 to the space between the cap A' and the end of the bushing C .

The chamber A^2 and space within the cap A' serve as a reservoir, which is charged with motive fluid through the ports c' during the interval when the enlarged portion D' of the piston moves the distance 90 between the point where it uncovers the ports c' and the end of its stroke toward the handle.

As the enlarged portion D' is greater in length than the distance between the two series of ports c' and c^2 , when the former is uncovered the latter is closed, so that motive fluid cannot be admitted through them to the working end of the cylinder.

The piston continues in its stroke toward the handle B until the ports d register with the annular chamber A^3 , as illustrated in Fig. 2, at which time 95 motive fluid is admitted through the ports d to the interior of the piston and thence to the working end of the cylinder, which in the 100 present embodiment of my invention consists in the closed end of the bushing C .

The greater area of the larger end of the piston is consequently subjected to pressure, and the piston immediately commences its stroke toward the tool.

The communication with the motive fluid is cut off as soon as the ports d pass out of register with the annular chamber A^3 , which occurs before the enlarged end 105 D' of the piston uncovers the series of ports c^2 through the bushing.

As soon as the ports c^2 are uncovered the pressure which has been 110 stored in the reservoir, consisting in the chamber A^2 and space in the hollow cap A' , discharges into the working end of the cylinder and adds impetus to the stroke of the piston.

Upon the ports d being uncovered by the chamber A^5 the working end of the cylinder exhausts through the ports a^5 , and the stroke 115 of the piston in the opposite direction—namely, toward the handle—commences by reason of the motive fluid being exerted upon the shoulder d' .

From the foregoing description it will be observed that the stroke of the piston toward the tool is commenced by motive fluid admitted through the piston to the working end 120 of the cylinder, while the stroke of the piston during that portion of its travel when the

ports *d* are closed by the restricted interior surface *A*⁴ of the cylinder is effected not merely by the expansion of the motive fluid which has been admitted directly to the working end of the cylinder from the supply, but also by the expansion into the cylinder of the motive fluid which has been charged in the reservoir prior to the admission of the motive fluid from the supply to the cylinder. By connecting the reservoir with the supply during the interval of the time occupied by the enlarged portion of the piston *D*' passing from the series of ports *c*' to the end of its stroke the reservoir is completely charged directly from the supply and only discharges into the working end of the cylinder after the stroke of the piston toward the tool has commenced by the admission of motive fluid through the ports *d* to the working end of the cylinder. It is also evident that by admitting the motive fluid through the relatively large ports *d* to the working end of the cylinder the entire expansibility of the fluid is utilized to impart initial movement to the piston and is not diminished by expansion from the working end of the cylinder into the reservoir.

While we have described more or less precisely the details of construction, we do not wish to be understood as limiting ourselves thereto, as we contemplate changes in form, the proportion of parts, and the substitution of equivalents as circumstances may suggest or render expedient without departing from the spirit of our invention.

Having now fully described our invention, what we claim as new, and desire to secure by Letters Patent, is—

1. In a fluid-pressure-operated tool, the combination with a cylinder, of a reciprocating piston therein, a reservoir, means for charging said reservoir prior to the admission of pressure to the working end of the cylinder and means for connecting said reservoir directly with the working end of the cylinder after the supply has been cut off, substantially as described.

2. In a fluid-pressure-operated tool, the combination with a cylinder, of a reciprocating piston therein, a reservoir, said cylinder having a supply-port and ports communicating with said reservoir controlled by the piston to connect said reservoir with the motive-fluid supply prior to the admission of fluid-pressure to the working end of the cylinder and to connect said reservoir with the working end of the cylinder after the motive-fluid supply has been cut off, substantially as described.

3. In a fluid-pressure-operated tool, the combination with a cylinder having supply and exhaust ports, of a reciprocating piston in said cylinder controlling said ports, a reservoir having separate supply and discharge ports controlled by the piston the former port adapted to be connected to the motive-fluid source prior to the admission of pressure to the working end of the cylinder and the lat-

ter port adapted to be connected to the working end of the cylinder subsequent to the cutting off of the supply thereto, substantially as described.

4. In a fluid-pressure-operated tool, the combination with a cylinder having a working chamber and a reduced bore, of a reciprocating piston fitting within said reduced bore and having an enlarged portion fitting within the working chamber, a reservoir having a port adapted to be uncovered and thereby connected with the source of supply by the enlarged portion of the piston during its stroke away from the tool and a separate port communicating with the working end of the cylinder adapted to be uncovered by said enlarged portion of the piston during its stroke toward the tool, substantially as described. 85

5. In a fluid-pressure-operated tool, the combination with a cylinder having a working chamber and a reduced bore, of a reciprocating piston fitting within said reduced bore and having an enlarged portion fitting within the working chamber, a reservoir having separate supply and discharge ports spaced apart a distance less than the length of said enlarged portion of the piston the former port adapted to be connected with the motive- 95 fluid source prior to the admission of pressure to the working end of the cylinder and the latter port adapted to be connected to the working end of the cylinder subsequent to the cutting off of the supply, substantially as 100 described.

6. In a fluid-pressure-operated tool, the combination with a cylinder having supply and exhaust ports, of a bushing having ports therethrough within said cylinder, a reservoir between said bushing and said cylinder, a reciprocating piston within said cylinder controlling the supply and exhaust ports and having a portion fitted within said bushing and controlling the ports therethrough whereby pressure is admitted to said reservoir from the source of motive fluid prior to the admission of pressure to the working end of the cylinder, substantially as described. 105

7. In a fluid-pressure-operated tool, the combination with a cylinder having an open end, of a bushing the exterior diameter of which is slightly less than the diameter of the open end of the cylinder, a cap secured within the open end of the cylinder and engaging an 110 end of said bushing, and a handle secured to the cylinder by said cap, substantially as described.

8. In a fluid-pressure-operated tool, the combination with a cylinder having an open end, 115 of a bushing fitting within said cylinder and having an exterior diameter less than the interior diameter of the cylinder around the bushing thereby forming a storage-space between the cylinder and bushing, a partition 120 within said bushing adjacent to one end thereof, a cap having a hollow chamber extending within the open end of said cylinder, said bushing having openings therethrough com- 130

municating with said storage-space and said chamber, and a reciprocating piston within the cylinder controlling the supply and discharge of pressure through the openings in the bushing, substantially as described.

9. In a fluid-pressure-operated tool, the combination with a cylinder having an exhaust-port and an annular chamber connected with the supply, of a differential reciprocating piston controlling the supply and exhaust from the working end of said cylinder, an exterior shoulder on said piston exposed to pressure in said annular chamber to effect the stroke of the piston away from the tool, a

reservoir having ports communicating therewith adapted to be uncovered by said shoulder and thereby connected with said annular chamber prior to the admission of pressure to the working end of the cylinder, substantially as described. 15

20 In testimony whereof we sign this specification in the presence of two witnesses.

HENRY H. VAUGHAN.

CHARLES HARRIS JOHNSON.
